UNITED STATES PATENT OFFICE.

FRED MERRILL HARGRAVE, OF CEDAR RAPIDS, IOWA.

PLANING OR SCARIFYING MECHANISM.

Original application filed September 15, 1925, Serial No. 56,508. Divided and this application filed January 25, 1927. Serial No. 163,499.

This invention relates to road building machines, more particularly to the surface planing or scarifying mechanism thereof, and is a division of my application filed September 15, 1925, Serial No. 56,508, and the invention has for its object, to provide in a manner as hereinafter set forth, for planing or scarifying the surface of a roadway, street or pavement.

Further objects of the invention are to provide, in a manner as hereinafter set forth, a mechanism of the class referred to which is comparatively simple in its construction and arrangement, strong, durable, thoroughly efficient in its use, conveniently adjusted, and comparatively inexpensive to set up.

With the foregoing and other objects in view, the invention consists of the novel construction, combination and arrangement of parts as hereinafter more specifically described, and illustrated in the accompanying drawings wherein is shown an embodiment of a cleaner or scarifier mechanism in accordance with this invention, but it is to be understood that changes, variations and modifications can be resorted to which fall within the scope of the claims hereunto appended.

In the drawings wherein like reference characters denote corresponding parts throughout the several views:

Figure 1 is a top plan view of a planer or scarifier mechanism, in accordance with this invention, for the purpose of planing or scarifying the surface of a roadway, street or pavement and further illustrating the adaptation of the mechanism in connection with a mobile support or rather the side members of the latter.

Figure 2 is a side elevation thereof showing the adaptation of the mechanism in connection with the side members of the mobile support.

Figure 3 is a cross sectional view of the mechanism.

Figure 4 is a section on line 4—4 Figure 1. Before specifically describing the elements of the planer or scarifying mechanism, it is thought advisable to briefly refer to the function and arrangement thereof. This mechanism comprises sets of heavy steel planer blades, rigidly held in position and with the cutting edge of each blade set at right angles with respect to the transverse axis of the machine or mobile support. Each set of

blades is so arranged that the length of the cutting edge of one blade is positioned to place the right end of each cutting edge directly behind the left end of the cutting edge of the next blade to the right. The result is that every inch of street surface is planed by a blade and there is space left between the blades for the passage of loose material. The blades of each set are independently adjustable from a vertical standpoint and both sets are bodily adjustable.

A planer or scarifying mechanism in accordance with this invention is adapted to be carried by a mobile support of any suitable type, which may include wheels and runners, and be of the type as disclosed in my application Serial No. 56,508. The mobile support may be self-propelled or operated as a trailer behind a tractor, truck or other motive power as referred to in my application Serial No. 56,508. The mobile support, other than the side members thereof, forms no part of the invention embodied in this application, and therefore it is thought unnecessary to specifically describe a mobile support, as by reference to my application Serial No. 56,508 the construction and arrangement of a mobile support, with which the mechanism in accordance with this invention is adapted, can be ascertained. The side members of the mobile support are indicated at 1 and 2.

The planer mechanism comprises a rectangular carrier 279 provided at its forward and its rear side with a set of vertically disposed spaced grooves. The grooves of the forward set are indicated at 280 and those of the rear set at 281. Each end of the carrier is formed with a pair of superposed spaced projections 282, 283 having arranged therebetween a shifting nut 284 for the carrier 279.

Secured to the inner faces of each side member of the mobile support, at the rear thereof, is a pair of vertically disposed spaced supports 285 and 286. The supports of each pair are oppositely disposed, and each is in the form of an angle bar of a length to extend a substantial distance above the sides of the mobile support. Each pair of supports have arranged below the lower ends thereof, a combined support and bearing block 287, provided with a socket 288 opening at the top thereof. The block 287 is secured to the pair of supports by the hold-

fast devices 289. Secured between the upper ends of each pair of supports is a bearing block 290, provided with a vertical opening 291. The block 290 is arranged in alignment with the block 287. The holdfast devices for the blocks 290 are indicated at 292. The projections 282 and 283, at each end of the carrier extend between the supports 285 and 286, and each of which is formed with a vertical opening 293 having a smooth wall. The openings 291, 293 and socket 287 are arranged in alignment.

The carrier, with the planer blades, is bodily adjustable from a vertical stand-point, and to provide for such adjustment a pair of simultaneously operable adjusting elements co-act with the nuts 284 at the ends of the carrier. Each of said elements consists of a shaft referred to generally by the reference character 294, and provided with an intermediate threaded portion 295 engaging with a nut 284. The shaft 294 extends through the block 290, projections 282, 283, nut 284 and seats in the socket 288. To arrest vertical movement of the shaft 294, it is provided with a collar or boss 296, which abuts against the bottom of the block 290. The nut 284 seats on the top of the projection 283, and has its upper face formed with a boss 297, bearing against the lower face of the projection 282. The upper end of each of the shafts 294, above the block 290 carries a worm pinion 298. Extending transversely of the machine and journaled in bearings 299, supported on brackets 300 which are secured to the vertical supports and 290, is an operating shaft 301, provided with a pair of spaced worms 302, meshing with the pinions 298 for simultaneously revolving the shafts 294, to provide for the vertical adjustment of the carrier 279. The shaft 301 carries at one of its ends a hand wheel 303 to facilitate the operation thereof manually.

The planer blades of one set are indicated at 304 and those of the other set at 305. Each of the blades is provided with an elongated shank. The shanks for the blades 304 are indicated at 306 and those for the blades 305 at 307. The shanks 306 are mounted in the grooves 280 and the shanks 307 in the grooves 281. The shanks of each set of blades are secured in their respective grooves by a holding plate 308 having a wooden liner 309 and by holdfast devices 310 which extend through a holding plate and its liner and engage in the carrier 279. The holding plates are arranged at the front and rear sides of the carrier 279. The securing means for the shanks 306 are arranged above the securing means for the shanks 307.

An adjusting screw is provided for each of the planer blades of a set. The screws for the front set are indicated at 311 and those

for the rear set at 312. Each adjusting screw rests on the top of the shank of that blade with which it associates. Carried on the lower end of each adjusting screw is a nut 313. The nuts on the lower ends of the adjusting screws for each set of planer blades are held down by a flat metallic bar 314, of the same length as the carrier, and formed with openings 315 for the passage of the screws. Each plate 314 carries a securing means 316 which binds against the bar 314. Filler blocks 317 are interposed between the nuts 313 to prevent the turning thereof.

Each of the planer blades is of substantially triangular contour, and has its cutting edge 318 set at a slight angle with respect to the transverse axis of the machine. The cutting blade projects forwardly from its shank and the length of the cutting edge is sufficient to place the right end of each cutting edge directly behind the left end of the cutting edge of the next two to the right. See Figure 4. The result is that every inch of street surface is planed by a blade and there is a space left between the blades for the passage of the loose material.

Although the carrier 279 is shown provided with tools of the planer type, it is obvious that the tool can be of other suitable form such as a scarifier. Three vertical adjustments are possible for this mechanism. One of which being that the entire machine may be raised or lowered at will on the wheels, another of which being that the planer mechanism may be raised or lowered on the frame of the machine at will and the remaining adjustment is that each individual planer blade may be vertically adjusted within the carrier 279 at will.

The adjusting mechanism for the carrier 279 provides for uniform elevation of each end thereof with relation to the main frame of the machine.

It is thought that the many advantages of a planer or scarifying mechanism, in accordance with this invention can be readily understood, and although the preferred embodiment of the invention is as illustrated and described, yet it is to be understood that changes in the details of construction can be had which will fall within the scope of the invention as claimed.

What I claim is:

1. In a road building machine, a supporting structure, a non-rotating carrier arranged within, extending transversely of and having its ends connected therewith, a set of surface working tools mounted in the front and in the rear face of said carrier, said sets permanently disposed vertically, means detachably connected with and extending across the front and rear faces of the carrier for securing said sets thereto, and means mounted at the front and rear of the top of the

carrier for adjusting the tools to vary the position thereof with respect to the road surface, the said last mentioned means providing for the independent vertical adjustment of each of the tools of each of the sets.

2. In a road building machine, a supporting structure, a carrier extending transversely thereof and having a set of vertical grooves in its front and in its rear, a set 10 of surface working tools mounted in the grooves at the front and at the rear of the carrier, means extending across and detachably connected to the front and to the rear face of the carrier for retaining said sets 15 of tools in said grooves, and means mounted on the front and rear of the top of the carrier for vertically adjusting the tools to vary the position thereof with respect to the road surface.

20. 3. In a road building machine, a supporting structure, a carrier extending transversely thereof and having a set of vertical grooves in its front and in its rear, a set of surface working tools mounted in the grooves 25 at the front and at the rear of the carrier, means extending across and detachably connected to the front and to the rear face of the carrier for retaining said sets of tools in said grooves, means mounted on the front 30 and rear of the top of the carrier for vertically adjusting the tools to vary the position thereof with respect to the road surface, and said last mentioned means providing for the independent vertical adjustment 35 for each tool of each of said sets.

4. In a road building machine, a supporting structure, a carrier extending transversely thereof and having a set of vertical grooves at its front and at its rear, a set of 40 surface working tools mounted in the grooves at the front and at the rear of the carrier, means connected to the front and to the rear of the carrier for securing said sets of tools in said grooves, means mounted on 45 the top of the carrier for vertically adjusting the tools to vary the position thereof with respect to the road surface, and means for connecting the ends of the carrier to said

supporting structure and said means further providing for the vertical adjusting of the 50 carrier relative to said supporting structure.

5. In a road building machine, a supporting structure, a carrier extending transversely thereof and having a set of vertical grooves at its front and at its rear, a set 55 of surface working tools mounted in the grooves at the front and at the rear of the carrier, means connected to the front and to the rear of the carrier for securing said sets of tools in said grooves, means mounted 60 on the top of the carrier for vertically adjusting the tools to vary the position thereof with respect to the road surface, said last mentioned means providing for the independent vertical adjustment for each tool 65 of each of said sets, and means for connecting the ends of the carrier to said supporting structure and further providing for the vertical adjusting of the carrier relative to 70 said structure.

6. A planer or scarifying mechanism comprising a non-rotating carrier, a set of surface working tools mounted in the front and in the rear face of said carrier, each of the tools of each of said sets including an elongated vertically disposed shank, the shanks of each set arranged in parallelism, each of the shanks of each of the tools of each set merging at its lower end in a planer blade of substantially triangular contour, means 80 abutting the front and rear face of the carrier and detachably connected to the latter for securing said sets thereto, and means mounted on the top of the carrier for adjusting the tools to vary the position thereof 85 with respect to the road surface.

7. A planer or scarifying mechanism in accordance with claim 6, the planer blades of the tools of each set having cutting edges thereof arranged with the right end of a cutting edge of a blade of a set positioned directly behind the left end of the cutting edge of the next blade to the right of each set.

In testimony whereof, I affix my signature hereto.

FRED MERRILL HARGRAVE.
